UNITED STATES PATENT OFFICE

DAVID CROSSLEY, OF TRENTON, NEW JERSEY

POWER PRESS

Application filed November 16, 1928. Serial No. 319,894.

My invention relates to power presses, and particularly to those types of presses in which a reciprocating plunger head is adapted to compress material in a die consisting of a relatively movable part and a stationary part.

An object of my invention is to provide certain improvements in such presses as employ a reciprocating compressing plunger connected to a horizontal wheel which is driven alternatively up or down by a pair of driving disks. In presses of this type it has been customary to provide means for bringing the horizontal wheel to rest as the plunger approaches the limit of its upstroke. It has heretofore been proposed to accomplish this object by disengaging the driving disks from the horizontal wheel as the plunger completes its upstroke, or by providing a brake to bring the horizontal wheel to rest as it approaches the upward limit of its travel. A serious objection to these arrangements is that they either allow the driving disk to remain in contact with the horizontal wheel when the latter is held against movement by a brake, thus causing wear of the parts in the form of a "flat spot" on the horizontal wheel, or they do not properly absorb the inertia of the horizontal wheel. It is an object of my invention to provide means for automatically disengaging the driving disks from the horizontal wheel as the plunger approaches the upward limit of its travel, and to combine with this arrangement a brake to bring the horizontal wheel to rest immediately after the driving disks have been placed in their neutral position. In other words, my invention contemplates means for disengaging the friction drive before the driven member is braked, so that the wearing of "flat spots" on the friction surface of the driven wheel is effectually prevented.

A further object is to provide a press of the reciprocating plunger type adapted to compress material in a two-part die with fluid pressure means for positioning the die parts automatically, under the control of an operator, as the compressing plunger head moves to and from the die. I accomplish this object by providing a valve and valve operating means to control fluid pressure for open-

ing the die to receive the material to be compressed, for removing fluid pressure as the plunger moves toward the die in its compressing stroke, and for reversing the fluid pressure to close or strip the die and eject the compressed material as the plunger moves away from the die after completion of the compressing stroke.

Another object is to provide means to make possible ready and accurate adjustment of the capacity of the die for receiving material to be compressed, thereby varying, at the will of an operator, the thickness of the resulting product. Various means have been proposed to regulate the die capacity, but so far as I am aware it has not been possible prior to my present invention to make this adjustment instantly and accurately while the press is in operation.

Other and further objects and advantages of the invention will appear as the description proceeds.

In the accompanying drawings which form part of this application for Letters Patent, which illustrate one embodiment of my invention, and in which like reference characters designate the same parts in the several views,

Figure 1 is a front elevation of a press embodying my invention;

Fig. 2 is also a front elevation, being a detail view of the lower part of Fig. 1, with certain of the parts shown in section;

Fig. 3 is a side elevation of the parts shown in Fig. 2;

Fig. 4 is a detail view of the brake and its appurtenant elements; and

Fig. 5 is a detail top plan view, taken on the line 5-5 of Fig. 1, showing the arrangement of the tripping dogs and roller.

Referring now to the drawings, and first to Fig. 1, the numeral 1 designates the side frame, 2 the upper cross member, and 3 the bed of a press, all bolted together in rigid, rectangular relation, and provided with legs 4 to bring the bed to a convenient height. Upstanding side brackets 5, 5a are secured to the upper cross member 2 and carry bearings 6 for the transverse drive shaft 7 which is continuously driven by any suitable means,

100

as, for example, by the electric motor 8 through the medium of the belt 9 and pulleys 10 and 11.

The upper cross member 2 is provided with a central hub internally threaded to receive the threaded spindle 12 which carries the non-rotating compressing plunger 13. This plunger is preferably polygonal in section and is adapted to reciprocate vertically in a slideway 14 secured between opposite portions of the side frame 1. The bottom of the plunger 13 is faced to form the plunger head 15, and fixed to the upper end of the spindle 12 is the horizontal wheel 16, which is provided about its periphery with a suitable friction surface 17, as, for example, leather. Keyed on the shaft 7, on opposite sides of the horizontal wheel 16, are a lowering disk 18 and a raising disk 19, a sufficient distance apart to enable them, when in the neutral position shown in Fig. 1, to be rotated just out of contact with wheel 16.

It will be apparent that when the shaft 7 is rotated the plunger head 15 will be raised or lowered, depending on which of the disks 18, 19 is brought into engagement with the horizontal wheel 16. This alternative engagement is effected by sliding the shaft 7 axially in its bearings 6, whether manually or automatically by the mechanism which will now be described.

The bracket 5a is provided with a horizontal arm 20 to afford a fulcrum for the bellcrank 21 which is forked at its upper end 35 to embrace the sleeve 22 rotatably mounted on the shaft 7, but fixed against axial movement along said shaft. The bellcrank is linked by means of the rod 23 and adjusting nuts 24 to a hand lever 25 pivoted conveniently on the bed of the press. The lever 25 is of the second order, so that when the parts occupy the position shown in Fig. 1, depressing this lever pulls down on the rod 23 and moves the shifting fork of the bellcrank 21 40 to the left to bring lowering disk 18 into contact with the friction surface 17 of horizontal wheel 16 and thus lower the plunger 13. The bearing 6 adjacent the raising disk 19 carries a tubular housing containing a coil spring 26 45 under compression, which bears against the end of the shaft 7 to urge the raising disk 19 into contact with the horizontal wheel 16. This spring 26 operates, through the parts 7, 22, 21 and 23, to lift the hand lever 25 when 50 released by the operator after completion of a downstroke of the plunger head 15, to bring the raising disk 19 into contact with the horizontal wheel 16 and thus raise the plunger head 15.

One object of my invention is to provide 55 positive and unfailing means for disengaging the raising disk 19 from the horizontal wheel 16 automatically as the plunger 13 approaches the limit of its upstroke, and to so dispose 60 such throw-off means that regardless of the

height to which the inertia of the rising parts, excess power of the motor 8, or any other cause may raise the plunger 13, the driving disks 18, 19, will be shifted only to their neutral position and no further, thus positively preventing, on the upstroke of the plunger 13, engagement of lowering disk 18 with horizontal wheel 16. I provide such means as follows:

Pivoted to the stationary upper cross member 2 of the press is a bellcrank 28, one arm of which is slotted to receive a pin 29 on the rod 23. The other arm of bellcrank 28 is adjustable, as by means of a roller carried by an adjusting screw 30. It will be appreciated that lifting the roller arm of bellcrank 28 will result in shifting shaft 7 to the left (in Fig. 1) to throw disks 18, 19, into their neutral position, and it will be further appreciated that if this lifting of the roller arm persists beyond a certain limit, the shifting of shaft 7 to the left will likewise continue, moving the disks beyond their neutral position, thereby engaging lowering disk 18 with the horizontal wheel 16.

In order to cause lifting of the plunger, regardless of the extent of the lift, to do no more than move the driving disks to their neutral position (in other words, to prevent excess upward movement of the plunger from causing engagement of lowering disk 18 with horizontal wheel 16), I provide an element movable with the plunger, adapted to contact with the roller arm of the bellcrank 28, to move the throw-off means to disengaging position during a portion of its contact, and to effect no further movement of the throw-off means during further relative movement of the element and the throw-off means.

One form of such element is shown in Fig. 1, consisting of a stem 27 mounted on the plunger 13, and having at its upper end a surface inclined to the axis of the plunger. When the rising plunger approaches the limit of its upstroke this inclined surface contacts with the roller arm of bellcrank 28, thereby actuating the throw-off means to move the driving disks to their neutral or disengaged position. The side of stem 27 below the inclined surface is formed parallel to the axis of the plunger, and this side contacts with the roller arm of bellcrank 28 during further upward movement of the plunger. The stem is so proportioned, and screw 30 may be so adjusted, that contact of the roller arm with the straight side of the stem during further traverse of these parts operates to communicate no further movement to the power throw-off means, but serves only to maintain the throw-off means in its disengaging position.

It will be appreciated that the mechanism just described effectually prevents the wearing of flat spots on the friction surface 17 of horizontal wheel 16 by preventing reverse

directional engagement of lowering disk 18 with this friction surface during the lifting of the reciprocating parts of the press.

In order to bring the reciprocating parts of the press speedily to rest at the end of their upstroke, I preferably provide a brake 31, bracketed to the rear of the upper cross member 2, and having its shoe adjusted to engage the upper side of the horizontal wheel 16 immediately after the moving parts of the press have brought sufficient of the inclined surface of stem 27 into contact with the power throw-off means to place the driving disks in their neutral position. Brake 31, it will be appreciated, engages wheel 16 only after the driving disks are shifted into neutral, its function being solely to absorb the inertia of the upwardly moving and rotating parts. This brake is the type usually employed in presses of this character, and will not be particularly described, the details of its construction sufficiently appearing in Fig. 4, which also makes clear the position in which it is mounted with relation to the wheel 16 and upper cross member 2.

A guide 32 may be provided for the stem 27 to support the latter against the bending stress of bellcrank 28. This guide consists of a short section of L-iron with one web bolted to the central hub of upper cross member 2, and the other projecting therefrom at right angles to afford a slide for one edge of the vertical stem 27.

The die which I have chosen to show in the embodiment of my invention illustrated in the accompanying drawings is one designed to produce at a single pressing a plurality of tiles. It consists of a number of stationary plungers 33 mounted on the press bed 3, and a die case 34 properly apertured to receive these plungers. This die case 34 constitutes the upper element of a rigid rectangular frame whose lower cross member is designated 35, and whose side members 36 pass through the bed 3, so that the rectangular diecase frame is capable of easy reciprocation relatively to the bed of the press.

Bolted to the under side of the bed 3 is a frame 37, the lower part of which provides a cylinder containing the piston 38 which is connected to the lower cross member 35 by the connecting rod 39. The latter passes out of the cylinder through the cylinder head 40, provided with the usual air tight packing 41. An air valve 42 at the side of the frame 37 has an air inlet 43 and upper and lower ports 44 and 45, by which air under pressure passing into the valve through the inlet 43 may be caused to lower and raise the piston 38.

The two-part die is therefore capable of assuming two positions. In Fig. 1 the die is shown in its closed or stripped position, the

hexagonal faces of the die plungers being flush with the surface of the die case. In Fig. 2 the die is shown in its open position, the die case being raised above its position in Fig. 1 to create pockets to receive the material to be compressed.

It will be understood, moreover, that the position of the die parts at any time will be determined by the position of the plungers in the valve 42, actuation of which is accomplished by the following means:

A pedal 46 is fulcrumed as a lever of the second order on a depending bracket 47 secured in the rear of the valve 42, and is connected to the valve rod 48 by the link 49. A coil spring 50 under tension between the pedal and press bed normally holds the pedal in its uppermost position, maintaining the double valve plungers at the highest of their three possible positions, so that air under pressure is admitted through upper port 44 to depress the piston 38 and strip the die.

When it is desired to raise the die case to create pockets for the "dust," the material which is to be compressed to form the tile, the pedal 46 is depressed. This lowers the valve plungers to their lowermost position, admits air under pressure through lower port 45, and places the upper port in communication with the atmosphere, thus lifting the piston 38 and with it the die case 34. Fig. 2 shows the parts in this position.

The third possible position of the valve plungers is one intermediate of the two just described. In this intermediate position both ports are in communication with the atmosphere and the die case 34 is capable of yielding under pressure of the plunger head 15, whereby the dust in the pockets is compressed.

In each pressing operation the valve 42 must be placed successively in the three positions just described, and it is an object of my invention to provide means for the automatic actuation of the valve as the other parts of the press are put through their necessary movements. I accomplish this purpose by certain novel means which will now be described as the operation of the press as a whole is explained.

The motor 8 being started so as to turn the belt 9 in the direction indicated by the arrow, whatever may be the initial position of the raising and lowering disks 19 and 18, they are at once brought to their neutral position, with the horizontal wheel 16 in its uppermost position, as shown in Fig. 1. An operator standing in front of the press then depresses the pedal 46, which brings the plungers of the valve 42 to their lowest position and lifts the die case 34, whereupon the dust is placed in the pockets formed by the die plungers 33 and the die case 34, flush with the surface of the die case, the parts then being in the position shown in Fig. 2.

The operator standing in front of the press then depresses the hand lever 25 to bring the lowering disk 18 into engagement with friction surface 17 of the horizontal wheel 16, and the plunger head 15 descends upon the die case. In order that the plunger head may compress the dust in the die pockets it is necessary that the die case be allowed to yield under pressure of the plunger head. Since in the operation of the press thus far described air pressure has been exerted against the underside of the piston 38, the plungers of the valve 42 must be moved to their intermediate position to place ports 44 and 45 in communication with the atmosphere. This is done automatically as the plunger head 15 moves toward the die, as follows:

Projecting horizontally from one side of the top of the plunger 13 is an arm 51, carrying a depending bracket 52, upon which are mounted, in staggered relation, as appears in Fig. 5, an upper dog 53 and a lower dog 54. These dogs are pivoted as shown; and stop pins and small coil springs maintain them normally horizontal, the upper dog being free to swing down, and the lower dog being free to swing up. It will be noted that the lower dog projects slightly farther to the right than does the upper dog. The valve rod 48 extends up as far as the slideway 14, where it is pin-connected to one arm of a bellcrank 55, which is pivoted to the slideway 14. The other arm of this bellcrank 55 carries a roller 56 adapted to contact with the dogs 53 and 54.

From the foregoing description it will be clear that in the operation just described, when the pedal 46 was depressed to raise the die case, the roller 56 was drawn to its innermost position. When the plunger 13 began its descent, lower dog 52 rode over the roller 56 without altering the position of the bellcrank 55. When, however, upper dog 53 contacted with roller 56, the bellcrank was moved slightly outward and there held by the upper dog 53, to lift the plungers of valve 42 to their intermediate position, the foot of the operator remaining on pedal 46 to oppose the lifting force of the spring 50 and hold the roller of bellcrank 55 against the upper dog 53. In this way only atmospheric pressure is exerted on both sides of the piston 38, and the die case is allowed to yield under pressure of the plunger head as the dust in the pockets is compressed.

When the compressing stroke has been completed the operator releases the hand lever 25, and the spring 26 pushes the raising disk 19 into engagement with surface 17 of the horizontal wheel 16, raising the latter until the stem 27 lifts the bellcrank 28, as shown in Fig. 1, to place disks 18 and 19 in their neutral position, while brake 31 brings the horizontal wheel to rest. Meanwhile,

lower dog 54 has contacted with roller 56 and moved bellcrank 55 to its outermost position. This lifts the plungers of valve 42 to their uppermost position, depressing piston 38 and so stripping the die, whereupon another operator, standing behind the press, may remove the compressed product. The first operator may then depress the pedal 46 to raise the die case; dust is placed in the die pockets, and all is in readiness for a second pressing operation.

When presses of the character described are used in the manufacture of tile, it is of great importance that the finished product be of uniform thickness. Of the several factors which principally affect the thickness of the tile produced by a given press, the most easily controlled is the depth of the die pockets into which the dust is inserted. However, even if the pocket depth be kept uniform over a period of time, the tile have been found by experience to vary considerably in thickness, some of the causes of the variation being different consistencies of dust used, changes in temperature and humidity of the atmosphere, and wear of the parts of the press. Heretofore, in order to effect adjustment of pocket depth when it is noticed that the tile are running too thick or too thin, it has been necessary to stop the machine and take up on whatever adjusting means may have been provided, which generally consisted in moving the die case up or down on the die side members. Besides necessitating that the press be stopped, the making of an adjustment of this kind is a matter of some nicety, requiring more skill than that usually possessed by the operator of a press, since the elevation of both sides of the die case must be exactly the same to maintain the die case precisely perpendicular to the axes of the die plungers.

It is an object of my invention to provide means for effecting accurate and instantaneous adjustment of the depth of the pockets while the press is in operation, by the operator who stands behind the press and who, by this act of removing the finished tile is best able to observe any variation in their thickness. The means which I provide eliminates the old adjustment of die case and side members, these parts being maintained in rigid relation with the lower cross member 35, but contemplates instead the provision of means to vary the upward limit of travel of the rectangular die case frame.

One means of accomplishing this object is shown in the drawings. Referring especially to Fig. 2, 57 designates a rod fixed into the upper side of the piston 38 in alignment with the connecting rod 39 and projecting from the cylinder head through a suitable packing nut 58. This rod 57 constitutes a follower for the cam surface 59 of the cylinder 60 which is journaled transversely of the

press in the upper part of the frame 37 and which is provided with a relatively large worm wheel 61. The latter meshes with a worm 62, the shaft 63 of which is carried out a convenient length to the rear of the press and terminates in the hand wheel 64. The bracket 65 is bolted to the bed of the press and supports the worm shaft near the hand wheel.

10 It will be apparent that by the construction just described the upward limit of travel of the die case 34 is directly determined by the contact of the cam surface 59 and the follower 57, the cam acting as an adjustable stop for the follower. The contacting part of the cam surface is varied at will by operation of the hand wheel 64, and since the turning of the cam is through a worm and gear, an exceedingly fine adjustment may be instantaneously made, with accuracy and precision, while the press is in operation.

It will be understood that I have shown and described but one specific embodiment of my invention, the details of which may be varied without departing from the spirit of the invention or the scope of the appended claims. For example, in the embodiment which I have shown, the hand wheel 64 is placed within convenient reach of the operator who stands behind the press and removes the finished tile. In a press designed to be worked by a single operator the hand wheel 64 will of course be on the same side of the press with pedal 46 and hand lever 25. I do not, therefore, wish to be limited to the specific construction shown and described, but regard as within the spirit of the broadest aspect of my invention any means for varying at will the limit of the relative displacement of a die case frame and die plunger, whether through the agency of a cam and follower, worm and gear, or otherwise, terminating in a manually controllable member, wherever located. Details may be varied to meet the exigencies of particular circumstances and requirements, but all are to be regarded as within the scope and purview of the appended claims.

Having thus described my invention, what I claim and desire to secure by Letters Patent is:

1. A die consisting of a movable and a stationary member, in combination with a frame connected to the movable member and carrying a follower, and means for adjusting the limit of motion of the follower.

2. A die consisting of a movable and a stationary member, in combination with a frame connected to the movable member and carrying a follower, and cam means for adjusting the limit of motion of the follower.

3. A die consisting of a movable and a stationary member, in combination with a frame connected to the movable member and carrying a follower, and a cam coacting with the

follower with its axis in fixed relation with the stationary member for adjustably determining the limit of motion of the follower.

4. A die consisting of a movable and a stationary member, in combination with a frame connected to the movable member and carrying a follower, a cam coacting with the follower with its axis in fixed relation with the stationary member for adjustably determining the limit of motion of the follower, and worm and gear means for turning the cam.

5. A die consisting of a movable and a stationary member, in combination with a frame connected to the movable member, a piston connected to the frame and operable by fluid pressure to move the frame, an adjustable stop, means connected to the piston and coacting with the stop to determine the range of movement of the movable member.

6. A die consisting of a movable and a stationary member, in combination with a frame connected to the movable member and carrying a follower, a cam coacting with the follower with its axis in fixed relation with the stationary member for adjustably determining the limit of motion of the follower, and manually controllable means for turning the cam disposed within easy reach of the operator who removes the finished product from the die.

7. A die consisting of a movable and a stationary member, in combination with a frame connected to the movable member, a piston connected to the frame and operable by fluid pressure to move the frame, a second frame in rigid relation to the stationary member, a cam carried by the second frame, and a cam follower carried by the piston to coact with the cam and limit the range of movement of the piston.

8. A die consisting of a movable and a stationary member, in combination with a frame connected to the movable member, a piston connected to the frame and operable by fluid pressure to move the frame, a second frame in rigid relation to the stationary member, a cam carried by the second frame, and a cam follower carried by the piston to coact with the cam and limit the range of movement of the piston, together with worm and gear means for turning the cam.

9. In a press of the character described, a compressing plunger, a horizontal wheel adapted when rotated to move the plunger, driving disks alternatively engageable with the horizontal wheel, means cooperating with the plunger to place the driving disks in a neutral position when the plunger approaches the limit of its upstroke, and a brake operating upon the horizontal wheel only after the driving disks are placed in their neutral position.

10. In a press of the character described, a compressing plunger, a horizontal wheel adapted when rotated to move the plunger,

70

driving disks alternatively engageable with the horizontal wheel, throw-off means for the driving disks, means cooperating with the plunger and the throw-off means to place the driving disks in a neutral position when the plunger approaches the limit of its upstroke, and a brake operating upon the horizontal wheel only after the driving disks are placed in their neutral position.

11. In a press of the character described, a compressing plunger, a horizontal wheel adapted when rotated to move the plunger, driving disks alternatively engageable with the horizontal wheel, throw-off means for the driving disks including a lever fulcrumed on the press, a stem on the plunger adapted to contact with an arm of the lever as the plunger approaches the limit of its upstroke to place the driving disks in their neutral position, and a brake operating upon the horizontal wheel only after the driving disks are placed in their neutral position.

12. In a press of the character described, a compressing plunger, a horizontal wheel adapted when rotated to move the plunger, driving disks alternatively engageable with the horizontal wheel, a control rod for the driving disks, a lever fulcrumed on the press with one arm pivoted to the control rod, a stem on the plunger adapted to contact with the other arm of the lever as the plunger approaches the limit of its upstroke to place the driving disks in their neutral position, and a guide on the press to support the stem against bending stress of the lever.

13. In a press of the character described, a compressing plunger, a horizontal wheel adapted when rotated to move the plunger, driving disks alternatively engageable with the horizontal wheel, a control rod for the driving disks, a lever fulcrumed on the press with one arm pivoted to the control rod, a stem on the plunger adapted to contact with the other arm of the lever as the plunger approaches the limit of its upstroke to place the driving disks in their neutral position, and an inertia-absorbing brake operating upon the horizontal wheel only after the driving disks are placed in their neutral position.

14. In a press of the character described, a compressing plunger, a horizontal wheel adapted when rotated to move the plunger, a raising disk and a lowering disk alternatively engageable with the horizontal wheel, manually controllable means for engaging the lowering disk with the horizontal wheel, means for urging the raising disk into engagement with the horizontal wheel as the plunger is driven downwardly, means actuated by the plunger for placing the disks in a neutral position as the plunger approaches the limit of its upstroke, and a brake operating upon the horizontal wheel

only after the driving disks are placed in their neutral position.

15. A die consisting of a movable and a stationary member, an element carried by the movable member, a cam carried by the stationary member, and means for adjusting the cam to vary the limit of motion of the element.

16. A die consisting of a movable and a stationary member, an element carried by the movable member, a cam carried by the stationary member, and means associated with the stationary member for adjusting the cam to vary the limit of motion of the element.

17. A die consisting of a movable and a stationary member, an element carried by the movable member in substantial alignment with the center of area thereof, a second element carried by the stationary member and adapted to be engaged by said first element during operation of the die, in combination with means for adjusting said second element to vary the limit of motion of said first element.

18. A die consisting of a movable and a stationary member, an element carried by the movable member, a second element carried by the stationary member and having a surface adapted to be engaged by said first element during operation of the die, in combination with means fixedly associated with the stationary member and connected with the second element for adjusting said second element to vary the limit of motion of said first element.

19. In combination with a press having a plunger, driving means for moving said plunger on its working stroke and other driving means for retracting said plunger, throw-off means adapted to be moved to disengaging position whereby said plunger is rendered inoperable by both of said driving means, and means for actuating said throw-off means comprising an element movable synchronously with the plunger and in contact with said throw-off means, said element being adapted by said contact to move said throw-off means to its disengaging position regardless of the extent of continued relative movement of said element and said throw-off means after the beginning of said contact.

20. In combination with a press having a plunger, driving means for moving said plunger on its working stroke and other driving means for retracting said plunger, throw-off means adapted to be moved to disengaging position whereby said plunger is rendered inoperable by both of said driving means, and means for actuating said throw-off means comprising an element movable synchronously with the plunger in contact with said throw-off means, said element being adapted during a portion of said contact to move said throw-off means to its disengaging position, and during the remainder

of its contact to communicate no further movement to said throw-off means.

21. In combination with a press having a plunger, driving means for moving said plunger on its working stroke and other driving means for retracting said plunger, throw-off means adapted to be moved to disengaging position whereby said plunger is rendered inoperable by both of said driving means, and means for actuating said throw-off means comprising an element movable synchronously with the plunger to traverse said throw-off means, said element being adapted during said traverse to move said throw-off means to its disengaging position, and during the remainder of its traverse to maintain said throw-off means in its disengaging position.

22. A press including a plunger, a horizontal wheel adapted when rotated to move the plunger, driving disks alternatively engageable with the horizontal wheel to raise and lower the plunger, in combination with power throw-off mechanism including means associated with the driving disks and adapted in one position to disengage said disks from said horizontal wheel, and a member associated with said plunger and movable synchronously therewith having a surface adapted to be engaged with said means, one portion of said surface being adapted to move said means to disengage said disks from said horizontal wheel, and another portion of said surface being adapted to maintain said disks disengaged from said horizontal wheel.

23. The combination claimed in claim 19, in which the throw-off means is a pivoted element, the means for actuating the throw-off means is a stem mounted on the plunger, and the surface of the actuating means adapted to contact with the throw-off means is in part inclined to the axis of the plunger and in part parallel therewith.

24. The combination claimed in claim 19, in which the throw-off means is a bellcrank pivoted to a stationary part of the press, and the means for actuating the throw-off means is a stem mounted on the plunger and adapted to be moved by the plunger into contact with an arm of the bellcrank, the portion of the surface of the actuating means first adapted to contact with the arm of the bellcrank being inclined to the axis of the plunger, and the remaining portion of said surface adapted to contact with the arm of the bellcrank upon further movement of the plunger being parallel to the axis of the plunger.

25. The combination claimed in claim 19, in combination with a member movable with said plunger and a brake adapted to engage said member after said throw-off means has been moved to its disengaging position.

In testimony whereof I affix my signature.

DAVID CROSSLEY.
